BUCKLE

Harry Chalfin, Brooklyn, N. Y.

Application May 18, 1934, Serial No. 726,232

2 Claims. (Cl. 24—178)

This invention relates, generally, to improvements in buckles; and the invention has reference, more particularly, to buckles of the kind utilized in the trimming and ornamentation of dresses and other articles of wearing apparel.

This invention has for its principal object to provide a novel construction of metallic buckle body comprising complementary front and back shells which, when assembled together, form an apertured frame having a cross bar within the aperture thereof, and wherein cooperative elements making up the cross bar are respectively formed as integral parts of the respective shells, being at the same time individually shaped so that one element strongly reinforces the other when the same are mutually engaged, whereby a rigid cross bar structure is obtained which is well adapted to resist bending or other deforming stresses, while nevertheless providing a neat and sturdy appearance.

This invention has for a further object to provide, in a buckle structure of the kind mentioned, mutually cooperative cross bar forming elements carried by and integral with the respective buckle body shells, said elements being automatically engaged in cooperative relation by the mere assembling of the shells together, so that a rigid cross bar is formed without necessity for employing separate or additional reenforcing bars, cores or wires; and to this end one shell of the buckle body is provided with a cross bar element of substantially semi-circular cross-sectional shape having its hollow side facing inward, while the other shell of the buckle body is provided with a cross bar element of tubular cross-sectional shape, whereby, when the shells are assembled together, the tubular element is entered within the hollow side of the semi-circular element and in contact therewith along its longitudinal axis, thus strongly bracing the same against bending or other deformation.

The invention has for other objects to provide a buckle body of the kind described which may optionally be covered or faced with textile or other flexible material adapted to harmonize with the material of the article of apparel with which the buckle is desired to be used, the marginal portions of such facing being clamped between the shells when the latter are assembled; and to provide a buckle body upon the cross bar of which may optionally be pivotally mounted a buckle tongue, in which case the cross bar elements may be provided with a transversely constricted bearing portion around which the eye or loop of such tongue is engaged.

Other objects of this invention, not at this time more particularly enumerated, will be understood from the following detailed description of the same.

An illustrative embodiment of this invention is shown in the accompanying drawing, in which:

Fig. 1 is a front face view of a buckle body according to this invention; and Fig. 2 is a rear face view of the same.

Fig. 3 is a sectional view, taken on line 4—4 in Fig. 1, drawn on an enlarged scale, but showing the complementary shells making up the buckle body opposed one to the other ready for assembly; Fig. 4 is a similar view with the shells operatively assembled together; and Fig. 5 is a sectional view, taken on line 5—5 in Fig. 1, drawn on an enlarged scale, and showing the shells operatively assembled to form the buckle body. Fig. 6 is a sectional view similar to that of Fig. 4, but showing the buckle body as provided with a facing of textile or other flexible material, and showing a buckle tongue pivotally engaged on the cross bar.

Fig. 7 is a fragmentary plan of a blank from which the front shell and its cross bar element is formed; and Fig. 8 is a similar fragmentary plan of a blank from which the back shell and its cross bar element is formed.

Similar characters of reference are employed in the hereinabove described views, to indicate corresponding parts.

Referring to the drawing, the front shell of the buckle body is preferably formed by a stamping of sheet metal, or is otherwise formed from other material, to comprise a front face wall 10 having an interior aperture 11. The peripheral shape of both said face wall and the interior aperture thereof may be of any desired form or design. Extending from the exterior margins of said face wall 10 is a rearwardly projecting peripheral flange 12; and, likewise, extending from the interior margins of said face wall 10, which bound said aperture 11, is a rearwardly projecting peripheral flange 13. A portion of the blank 10' from which said front shell is formed is shown in Fig. 7, wherein the aperture 11 is shown surrounded by marginal portions 13' from which are struck the bounding peripheral flange 13 of the finished front shell. Integrally connected by neck portions 14 of reduced width, which join its respective ends to blank 10' respectively at opposed sides of the aperture 11, is a blank portion 15' which lies across said aperture 11. This blank portion 15' is provided with free longitudinal marginal portions 15''. When the blank 10' is

formed by suitable tools or dies into the finished front shell of the buckle body, said marginal portions 15" are inwardly curled or bowed transversely of the blank portion 15', thereby producing a front cross bar element 15 of substantially semi-circular cross sectional shape to provide an inwardly facing hollow side or open channel 16 extending throughout the length of the cross bar element 15.

10 The back shell of the buckle body is likewise preferably formed by a stamping of sheet metal, or is otherwise formed from other material, to comprise a rear face wall 17 having an interior aperture 11'. The peripheral shape of both said 15 rear face wall 17 and the aperture 11' correspond in form and design to like parts of the front shell. Extending from the exterior margins of said rear face wall 17 is a forwardly projecting peripheral flange 18; and, likewise, extending 20 from the interior margins of said rear face wall 17, which bound its aperture 11', is a forwardly projecting peripheral flange 19. The dimensions of the back shell as compared with the front shell are such that the forwardly projecting peripheral 25 flanges 18-19 of the former will telescope within the rearwardly projecting peripheral flanges 12-13 of the latter, when the shells are assembled together in buckle body forming relation. A portion of the blank 17' from which said back shell is 30 formed is shown in Fig. 8, wherein the aperture 11' is shown surrounded by marginal portions 19' from which are struck the bounding peripheral flange 19 of the finished back shell. Integrally connected by neck portions 20 of reduced width, 35 which join its respective ends to the blank 17' respectively at opposed sides of the aperture 11', is a blank portion 21' which lies across said aperture 11'. This blank 21' is provided with free longitudinal marginal portions 21". When the 40 blank 17' is formed by suitable dies or tools into the finished back shell of the buckle body, said marginal portions 21" are inwardly curled until their free longitudinal margins abut, thus producing a back cross bar element 21 of tubular 45 form and of a transverse diameter less than that of the front cross bar element 15 of the front shell.

45 The front and back shells having been produced and formed as above described, the same are ready to be assembled in buckle body forming relation. This is done by merely opposing the inner or flanged sides of the shells one to the other in the manner indicated in Fig. 3 of the drawing, and thereupon pressing the same together so that the flanges 18-19 of the back shell telescope into the flanges 12-13 of the front shell. The assembled shells may be secured together against accidental separation, by inwardly crimping over the free edge portions of the flanges 12-13 about the margins of said back shell, as 50 will be obvious from an inspection of Figs. 4 and 5 of the drawing. When the back shell is thus brought into operative assembled relation to the front shell, the tubular cross bar element 21 of the former will be entered within the channel 16 of the open hollow cross bar element 15 of the latter, and will contact said cross bar element 15 all along its longitudinal axis, so that the strong and bend resistant tubular element 21 will 55 strongly and firmly brace the hollow element 15, whereby together these parts provide a very strong and rigid composite cross bar structure integral with the buckle body, and well adapted to resist bending stresses or accidental undesired deformation. At the same time, the greater width 60 of the cross-bar element 15 as exposed to view at

the front of the buckle body provides a sturdy appearance, and one of better proportional balance than is provided by flat bars or wires, such as have frequently been heretofore provided in buckles of this class.

5 The buckle bodies are sometimes used without pivotal tongues; but, on the other hand, it is often desirable to provide a buckle tongue. In the latter case, the cross bar structure according to this invention is well adapted to support such 10 tongue, and in such event it is desirable to provide the cross bar structure with a restricted bearing portion 22 to receive the eye 23 of such a buckle tongue 24, as shown in Fig. 6. This restricted bearing portion 22 is formed by pinching in the 15 opposite lateral sides of the cross-bar element 15 against the sides of the tubular cross bar element 21, thus not only compacting the structure to better journal the eye 23 of the tongue 24, but also forming shoulders 25 which tend to maintain the 20 tongue against shifting displacement from desired location on the cross bar.

It is frequently desired to face the buckle body with a material harmonious with the appearance of the material of the wearing apparel with which 25 the buckle is to be used. This may be done with the buckle body structure of the instant invention in the customary manner, viz. by applying the selected facing material or fabric F over the face of the front shell, and then engaging the margins 30 f of such material or fabric around the flanges 12-13 of said front shell before assembling the back shell therewith, whereupon when the flanges 18-19 of the back shell are telescoped into the front shell flanges 12-13, said facing material F 35 will be drawn tautly over the face of the front shell and then secured by the clamping of its margins f between the flanges of the assembled shells, all as illustrated in Fig. 6 of the accompanying drawing.

40 From the above description it will be apparent that the instant invention provides a very simple buckle frame or apertured body having an integral cross bar structure within the aperture thereof which is of good appearance, and of exceedingly strong and rigid character, while at the same time being so made and assembled as to eliminate all necessity for extra separable parts, as well as eliminating the requirement of any extra or special tools for securing, reinforcing 50 or other finishing operations with respect to said cross bar structure per se, after the shells have been covered and assembled.

Having thus described my invention, I claim:

1. A buckle body comprising an apertured front shell having exterior and interior rearwardly projecting peripheral flanges, a correspondingly apertured back shell having exterior and interior forwardly projecting peripheral flanges to telescopically engage the flanges of said front shell 55 when said shells are operatively assembled together, said front shell having integral therewith to lie within and across the aperture thereof a hollow cross bar element of substantially semi-circular cross sectional shape with its open side 60 inward, and said back shell having integral therewith to correspondingly lie within and across the aperture thereof a tubular cross bar element formed by inwardly bent longitudinal marginal portions having their free edges meeting in 65 abutting relation along the inner side thereof to form a closed seam, said tubular cross bar element being of less diameter than the width of said semi-circular cross bar element and adapted to enter the open side of the latter to engage its 70

seamed side in centrally disposed longitudinal bracing contact therewith when said shells are assembled together.

2. A buckle body comprising a pair of complementary apertured shells adapted to be interengaged together in parallel relation, a cross bar element, neck-portions integrally joining the respective ends of said cross bar element to one shell respectively at opposite sides of the aperture of the latter, the longitudinal marginal portions of said cross bar element being turned transversely inward to give the latter an inwardly open substantially semi-circular cross-sectional shape, a second cross bar element, neck portions integrally

joining the respective ends of said second cross bar element to the other shell respectively at opposite sides of its aperture, the longitudinal marginal portions of said second cross bar element being transversely curled inwardly to abutting relation to give said second cross bar element a seamed tubular form smaller in diameter than the width of said semi-circular cross bar element, and said tubular cross bar element being entered within the open side of said first cross bar element to engage its seamed side in axial bracing contact with and along the length thereof when said shells are assembled together.

HARRY CHALFIN.
